DOOR LATCH

Leonard A. Marquardt, Elmhurst, Ill., assignor to
 W. H. Miner, Inc., Chicago, Ill., a corporation of
 Delaware

Application May 7, 1938, Serial No. 206,581

1 Claim. (Cl. 292—136)

This invention relates to improvements in door latches.

One object of the invention is to provide an automatically operating latching means for 5 swinging doors adapted to hold the doors in open position.

Another object of the invention is to provide latch means of the character indicated in the preceding paragraph especially adapted for 10 hinged doors of refrigerators cars, the latch means being especially designed to be easily operated to release the same when the edge of the door is grasped to swing the same away from the car wall to closing position.

15 Other objects of the invention will more clearly appear from the description and claims hereinafter following.

In the drawings forming a part of this specification, Figure 1 is a side elevational view of a 20 portion of a refrigerator car having a pair of hinged doors, illustrating my improvements in connection therewith. Figure 2 is an enlarged horizontal sectional view, through a portion of the car wall and a portion of one of the doors shown in Figure 1, illustrating the door swung 25 to fully open position against the car wall and showing my improvements in plan in connection therewith. Figure 3 is a vertical sectional view, corresponding substantially to the line 3—3 of 30 Figure 2. Figure 4 is an elevational view looking from right to left in Figure 3 with the keeper omitted and illustrating in connection therewith a different embodiment of the invention.

In said drawings, the side wall of the car is indicated by 10, the same having the usual side 35 door opening 11 closed by a pair of hinged doors 12 and 13. The door 12 is closed first and latched in closed position by well-known rotary latch elements 14 and 15 cooperating with the top and bottom portions of said door. The door 13 is 40 swung to closed position after the door 12 has been closed and latched and is then forced tightly shut by any suitable means, for example, a rotary keeper engaging crank bar 16 cooperating with keepers 17—17 on the car wall. When the 45 doors are opened they are swung outwardly against the car wall.

In carrying out my invention, I employ a latching mechanism for each door for holding the same in open position, comprising broadly a 50 supporting bracket A on the door; a pivoted latch element B on the bracket; and a keeper element C fixed to the car wall in cooperative relation with the latch element.

The supporting bracket A is in the form of a 55 plate member 18 narrowed between its top and bottom ends to provide laterally extending securing ears 19—19 and 19—19. At said narrowed portion, the plate 18 is provided with laterally spaced outstanding pivot lugs 20—20 having 60 horizontally aligned pivot pin-receiving open-

ings. The supporting bracket A is secured to the door near the bottom thereof and closely adjacent its outer or free edge, as most clearly shown in Figures 1 and 2, any suitable fastening elements being employed for this purpose, as for 5 example, screws extending through the ears 19—19 and into the door.

The latch element B is preferably in the form of a casting having an outstanding arm 21 provided with a keeper engaging hook 22 at its outer 10 end. The latch element B is pivotally supported between the lugs 20—20 of the supporting bracket A by a pivot pin 23 in the form of a headed rivet extending through the openings of said ears and a suitable opening in the element B. As shown 15 most clearly in Figure 3, the latch element B is further provided with an upstanding finger piece 24 by which the same may be manipulated. This finger piece is normally inclined outwardly away from the outer surface of the door whereby 20 sufficient clearance is provided to swing the latch element to disengage or unlock the same from the keeper C. The latch element is gravity influenced and is held in the normal position shown in Figure 3 by a flat stop face 25 in back 25 of and generally beneath the pivotal axis of said latch element. This flat stop face 25 is adapted to engage the outer face of the plate member 18 of the supporting bracket A. The hook 22 of the latch element B is so arranged that the keeper engaging portion thereof is disposed mainly below a horizontal plane coincident with the pivotal axis of the element B when the latter is in the normal position, thereby assuring proper locking engagement thereof with the keeper element. A recess 26 is thus provided between the 30 hook 22 and the main body of the latch element B. The rear wall of this recess presents a substantially vertical abutment face 27 parallel to the stop face 25 hereinbefore described. The hook 22 preferably has an upwardly inclined 35 outer slightly curved face 28 adapted to cam the latch member upwardly to effect automatic engagement thereof with the keeper element when the door is swung into open position against the car wall. As further shown in Figure 3, the 40 inner face of the engaging end of the hook 22 is slightly undercut, as indicated at 29, to properly interlock with the keeper element C.

The keeper element C is also in the form of a casting and comprises a substantially rectangular 50 base plate 30 having a horizontally disposed eye member extending therefrom. The eye member comprises a pair of outstanding spaced side arms 31—31 extending from the plate and connected at their outer ends by a transversely curved section 32. An elongated opening 33 is thus provided for the eye member adapted to receive the hook 22 of the latch element B. The keeper element C is secured to the side wall of the car by any suitable fastening elements, for example, 55 60

screws extending through the base plate 30 and into the wall 10. The keeper element C is so located that the hook 22 of the latch element B will register therewith when the door is swung 5 to fully open position against the car wall 10, and the curved section 32 permits proper engagement of the hook 22 therewith in the angular position of the door with respect to the car side wall when the door is swung to its fully open 10 position. As will be evident, by providing the keeper element C with this curved section 32, which forms, in effect, a rounded eye portion, the keeper element will properly cooperate with either the left or right hand door, the same being 15 universal to allow for the difference in angularity of the two doors with respect to the car wall. The outer top edge of the section 32 is rounded off, as indicated at 133, to present a cam face over which the cam face 28 of the hook 22 of the latch B may ride to effect lifting of said latch element when the same is pushed against the keeper C as the door is swung open. The inner face of the section 32 of the eye is undercut, as indicated at 34, to assure interlocking 20 of the hook 22 of the latch B with the keeper C. The outer face of the section 32 is substantially straight in a vertical direction, thereby providing an abutment surface 35 adapted to cooperate with the abutment face 27 of the latch element B to limit movement of the door toward the car 25 wall, the keeper C thus acting also as a door check or stop.

As will be evident upon reference to Figure 3, when swinging movement of the door is checked by engagement of the stop or abutment face 27 of the latch element B with the stop or abutment face 35 of the keeper C, the stop or abutment face 25 of the latch B bears on the plate 18 of the bracket A and pressure is transmitted 30 directly through the body of the latch element B to the plate 18, thereby relieving the pivot pin 23 from undue strain. It is further pointed out that the opening 26 of the latch B is of such a depth that, in the normal position of the latch element, the top wall of said recess or, in other 35 words, the underneath side of the horizontal arm 21, is spaced a predetermined distance above the eye of the keeper C, thereby allowing for unavoidable sagging of the door which may after a time occur due to the great weight of said door, and still assure proper locking engagement of the latch B with the keeper C. This predetermined clearance is slightly in excess of the normal amount which a door will sag in service so that 40 there will be no danger of the lower edge of the arm 21 coming into engagement with the top of the eye portion of the keeper C prior to downward swinging movement of the latch being stopped in the normal position shown in Figure 3, thus assuring full engagement of the undercut 45 inner face 29 of the hook 22 of the latch B with the cooperating undercut face 34 of the eye of the keeper element C. As shown in Figure 2, the undercut face 29 is convex or curved transversely to truly seat against the face 34 of the curved section 32 of the eye of the keeper C.

When either door of the refrigerator car is swung open, the hook 22 of the latch B of said door rides over the transverse section 32 of the eye of the keeper C and drops into the opening 50 of said eye, movement of the door being positively checked by engagement of the abutment face 27 of the latch element B with the stop face

35 of the keeper C. As shown in Figure 3, the parts are so proportioned that clearance is provided between the hook 22 of the latch B and the inner side of the curved section 32 of the eye of the keeper C, when movement of the door is checked, whereby the hooked end of the latch element is free to drop into the eye of the keeper. 5

To swing the door from its fully open position against the car wall to close the same, the operator grasps the edge of the door and at the same time manipulates the latch B to swing it out of engagement with the keeper element C. This can be accomplished by the use of one hand alone, as the latch is located closely adjacent the edge of the door so that the finger piece 24 thereof 15 may be pressed open and swung against the door at the same time that the edge of the door is grasped.

In Figure 4 the finger piece 24 of the latch B is shown as provided with a cross piece 36 at its 20 upper end, thereby presenting a T-shaped operating handle portion. This arrangement brings the finger grip portion of the finger piece nearer the edge of the door than in the type of finger piece shown in Figure 3, thereby making the 25 former still more accessible for operation by the hand used in grasping the door. It is further pointed out that by the use of the T-shaped handle portion, the latch, together with its supporting bracket, is universal so that it may be applied to either door, projecting portions of the T of the operating handle providing lateral extensions from the finger piece at opposite sides of the handle so that, when the device is applied to the right hand door, one of said extensions 35 lies at the free edge of said door, and when applied to the left hand door the other extension lies near the free edge of the latter.

I have herein shown and described what I now consider the preferred manner of carrying out 40 my invention, but the same is merely illustrative and I contemplate all changes and modifications that come within the scope of the claim appended hereto.

I claim:

In a door latch for a hinged door member adapted to be swung to open position against a wall member, the combination with a bracket secured to the outer side of one of said members, said bracket presenting a flat abutment face parallel to the plane of the door; of a latch element pivoted to said bracket for swinging movement on a horizontal axis, said latch element having an outstanding arm provided with a downturned hooked end; a flat abutment face on said latch element swingable into flat faced engagement with said abutment face of the bracket to limit movement of said latch element and normally maintain said arm in horizontal position; an abutment face on said latch element below said arm and inwardly of said hooked end thereof, said last named abutment face being parallel to said second named abutment face; a keeper fixed to the other of said members, said keeper having an outstanding horizontally disposed eye portion with which said hooked end of the arm is engageable; and a vertical abutment face on the outer side of said eye portion engageable by said third named abutment face of said latch element in a plane below the horizontal plane of the 45 pivotal axis of said latch. 50

LEONARD A. MARQUARDT.
